UNITED STATES PATENT OFFICE.

WILLIAM C. GROENIGER AND JOHN C. CROMWELL, OF COLUMBUS, OHIO, ASSIGNEES,
BY MESNE ASSIGNMENTS, TO THE TESTITE COMPANY, A CORPORATION.

CLOSET CONNECTION.

Application filed January 12, 1923. Serial No. 612,173.

The present invention relates broadly to drainage connections, and more particularly to connections of the type especially adapted for use between closet bowls and soil pipes.

5 It is essential that connections of this character be both gas and water tight. It is also desirable that they be of such nature that it will be unnecessary to specifically shape the outlet horn of the closet bowls. 10 This invention provides these desirable characteristics in an easily installed and comparatively inexpensive fitting.

In the accompanying drawings there is shown for purposes of illustration only a 15 preferred embodiment of this invention, it being understood that the drawings do not define the limits of this invention and that changes may be made in the construction disclosed without departing from the spirit 20 of the invention or scope of our broader claims.

In the drawings,

Figure 1 is a vertical sectional view through the lower portion of a closet bowl 25 and the upper portion of a soil pipe illustrating our improved connection;

Figure 2 is a top plan view of the connecting member;

Figure 3 is a vertical sectional view, corresponding to Figure 1, on an enlarged scale, illustrating the parts in position before compression of the packing gasket;

Figure 4 is a view, corresponding to Figure 3, showing the gasket compressed, 35 and

Figure 5 is a transverse sectional view on the line V—V of Figure 2.

In carrying out the present invention, there may conveniently be provided a floor 40 flange 2 in the nature of a casting, such as cast iron, of generally annular shape. This casting may have slots 3 for the attachment thereof to the base flange of the closet bowl as is understood in the art.

45 Preferably, the flange is shaped to provide a plurality of substantially equi-distantly spaced pockets 5, which pockets are adapted to receive the outwardly bent ends 6 of legs 7 extending upwardly from a packing receiving seat 8. The packing receiving seat 8 and the legs 7 may be of integral construction and are preferably of a comparatively non-corrodible material such as bronze. It has been found that the ends 6 may be

55 easily spot welded in position within the pockets 5 whereby the parts are held in assembled relationship.

The inner surface of the floor flange 2 is conveniently tapered to provide an opening of gradually decreasing cross-section away 60 from the outlet horn 9 of the closet bowl with which the connection is used. The legs 7 are also so dimensioned that when welded in position their outer surfaces will be spaced from the tapered inner surface of the 65 floor flange an amount substantially equal to the average thickness of a soil pipe, such as the pipe 10, to which connection is to be made. The base portion 11 of the packing receiving seat has an external diameter 70 which is substantially equal to the internal diameter of the soil pipe 10, whereby it may tightly engage the same when slipped into position within the upper end of the 75 pipe.

When it is desired to make connection with the soil pipe, a portion of the upper end thereof may be flared outwardly in any desired manner. This flared portion will then easily receive the base portion 11 of the 80 packing receiving seat and the diverging legs 7 which support the same. As the seat continues to slide into position, the upper edge of the soil pipe will be forced into the spaces between the legs and the floor flange 85 whereby it will be securely gripped, and the base portion 11 of the seat 8 will engage the interior of the soil pipe.

In order to permit the seat 8 to be tightly sealed in position within the soil pipe, it has 90 a portion of its outer wall cut away to provide a recess 12 between the same and the inner wall of the soil pipe. The seat is then preferably soldered in position by flowing solder into the recess 12, as will be readily 95 apparent to those skilled in the art. In Figure 4, the seat is shown soldered in position.

For forming a seal between the lower end of the outlet horn 9 and the connection, the 100 seat 8 is provided with a groove 13 which is preferably of tapered cross-section decreasing in width downwardly. This groove is adapted to receive the projecting flange 14 of a compressible gasket 15, the upper portion 105 of which directly engages the outlet horn. While this gasket may be of any desired construction, it is preferably construct-

ed as disclosed in the accompanying application of John C. Cromwell, filed January 12, 1923, Serial No. 612,258.

In Figure 3, the gasket is shown before it is compressed while in Figures 1 and 2 the gasket is shown as substantially completely compressed. It will be understood that the packing groove 13 holds the packing in the desired position, and that the compressing force is exerted on the packing in a direction substantially at right angles to the flat lower end of the outlet horn.

At the present time, it is customary to construct closet bowls with both long and short outlet horns. We have disclosed herein a bowl having a long outlet horn. It will be understood, however, that in order to accommodate horns of different lengths, it is only necessary to vary the length of the legs 7.

The advantages of the present invention arise from the provision of a connection which is easily made and which forms a tight seal between the closet bowl and the soil pipe.

We claim:

1. In a drainage connection, a closet bowl having an outlet horn, a soil pipe, an annular floor flange surrounding the upper end of said pipe, a packing receiving seat extending within said pipe, and means securing said seat to said flange, said means extending upwardly through the annular flange and being spaced therefrom to provide a soil pipe receiving recess therebetween, substantially as described.

2. In a drainage connection, a closet bowl having an outlet horn, a soil pipe, an annular floor flange surrounding the upper end of said pipe, a packing receiving seat extending within said pipe and having a packing receiving groove therein, and means securing said seat to said flange, said means extending upwardly through the annular flange and being spaced therefrom to provide a soil pipe receiving recess therebetween, substantially as described.

3. In a drainage connection, a closet bowl having an outlet horn, a soil pipe, an annular floor flange surrounding the upper end of said pipe, and a packing receiving seat extending within said pipe and having a welded connection with said flange, said seat and welded connection being so disposed with relation to the inner wall of the annular flange as to provide a soil pipe receiving recess therebetween, substantially as described.

4. In a drainage connection, a closet bowl having an outlet horn, a soil pipe, a floor flange surrounding the upper end of said pipe, a packing receiving seat extending

within said pipe, said seat having an external diameter substantially equal to the interior diameter of said pipe and adapted to engage the interior wall thereof, and upwardly and outwardly diverging legs securing said seat to said flange, substantially as described.

5. In a drainage connection, a closet bowl having an outlet horn, a soil pipe, a floor flange surrounding the upper end of said pipe, and a packing receiving seat carried by said flange and extending within the pipe, said seat having an external diameter substantially equal to the internal diameter of said pipe and having a portion thereof cut away to provide a packing receiving space between the seat and the wall of the pipe, substantially as described.

6. As an article of manufacture, a closet connection comprising an annular floor flange adapted to surround the upper end of a soil pipe, a packing receiving seat, and legs extending upwardly from said seat and through the flange in spaced relation to the inner wall thereof, said legs being welded to said flange, substantially as described.

7. As an article of manufacture, a closet connection comprising a floor flange, a packing receiving seat, and legs extending upwardly from said seat and welded to said flange, said legs providing a soil pipe receiving space between the same and one surface of said flange, substantially as described.

8. As an article of manufacture, an outlet connection for closet bowls comprising an annular floor flange having pockets formed in its upper surface, a gasket receiving seat, and legs extending upwardly from said seat and provided with portions welded in position within said pockets, substantially as described.

9. As an article of manufacture, an outlet connection for closet bowls comprising an annular floor flange, a gasket seat, and means connecting said seat and said flange, said means being spaced from the inner surface of said flange to provide a soil pipe receiving recess therebetween, substantially as described.

10. In a drainage connection, a closet bowl having an outlet horn, a soil pipe having a flared upper portion, a floor flange surrounding said outlet horn and said pipe, a gasket receiving seat carried by said flange and extending within said pipe, and a gasket on said seat in alignment with said outlet horn, substantially as described.

In testimony whereof we have hereunto set our hands.

WILLIAM C. GROENIGER.
JOHN C. CROMWELL.
